UNITED STATES PATENT OFFICE.

JAMES E. STOUT, OF HANOVER, PENNSYLVANIA.

AUTOMATIC PHONOGRAPH.

Application filed May 17, 1921. Serial No. 470,301.

To all whom it may concern:

Be it known that I, JAMES E. STOUT, a citizen of the United States, residing at Hanover, in the county of York and State of Pennsylvania, have invented certain new and useful Improvements in Automatic Phonographs, of which the following is a specification.

This invention relates to certain new and useful improvements in talking machines or disk phonographs of that general type known as self-operating or automatic in that provision is made for the automatic presentation and removal of a record, manual manipulation or attention being entirely dispensed with after the records are once placed in the magazine.

The present invention differs essentially from prior devices of this general character in that the records are not dropped onto the turn table, but the turn table is caused to be moved vertically to receive the records whereby all danger of injury to the records is avoided, and furthermore after each record is played this vertical movement of the turn-table, slightly downward, serves to clear the needle and reproducer portion while they are swept aside to allow the turn-table to ascend for a new record, also after a new record has been taken on to the turn-table it descends to a point to clear the needle and then rises gently against the predisposed needle. Another function accomplished by the same vertical movement is to restore the records to their original position after all the records have been deposited on the turn-table, this making it possible to play a program continuously.

The present invention has for its objects, among others to provide an improved device of this character in which the parts are compactly arranged so as to economize space, comparatively few in number, those readily assembled and not liable to injury or damage.

Briefly stated, the invention comprises mechanism for releasing the bottom record of a plurality of superimposed records, in the present instance shown as ten in number, but this number may be varied at will without departing from the spirit of the invention, or any material modification of parts. This mechanism is actuated by contact or impingement of the edge of the turn table, or the record or records already thereon, upon latches containing the stack of records,

the turn table being caused to be moved vertically from its plane of playing the top record to the lower surface or bottom of the bottom record in the magazine. Upon playing the last record in the magazine the restoring latches are brought into action by which the records that have been played and now supported on the turn table are restored to the magazine to be again delivered to the turn table or to be removed, to be replaced by others, by the elevation of the turn table.

Provision is made for the proper adjustments for the various elevations of the turn table on playing the records stacked thereon according to the height to which the turn table is raised upon taking off a record from the magazine.

At the end of each record the turn table is lowered to clear the needle of the reproducer, whereupon the tone arm and reproducer portion are swept aside, and then the turn table is elevated and the lowermost record in the magazine is released and deposited upon the turn table, or the top record already thereon, the upper surface of which is in close contact therewith so as to avoid any material drop of the record. The turn table is then lowered to clear the needle which is brought to a position above the playing edge of the record when the turn table is elevated against the point of the needle at the start of the groove in the record. The whole cycle of steps is carried out by mechanism located below the motor board and contained in a suitable case or frame which also contains the magazine posts. The turn table is rotated by suitable means, as a friction clutch, which is driven by a worm gear, the driving worm being carried by the governor shaft which is driven preferably by an electric motor. This worm also engages and rotates a cam shaft gear and upon engagement of a tooth clutch, the cam shaft. This cam

shaft embodies two cams, one cylindrical with the helical track, and the other a flat disc. The cylindrical cam raises and lowers the turn table by acting upon a thrust bearing at the lower end of the turn table spindle. The disc cam operates a lever engaged by the tone arm to swing it back from the centre of the record clear of the moving turn table and then back to the edge at the periphery of the record. One complete rotation of the cam shaft brings about the entire changing of the records. The cam shaft

is released and drops into engagement by a latch which is operated from a carriage composed of two parts and moved along a threaded shaft, one part of which carriage 5 engages the thread, the other part engaging the tone arm lever, thus synchronizing the motion of the two parts. When the needle has reached the end of the sound groove in playing a record, its cross-wise travel is 10 stopped, thereby stopping the movement of one part of the carriage, the other part still being engaged by the thread of the rotating shaft continues its travel a few revolutions by virtue of which the two parts of the carriage are disengaged letting in the cam shaft clutch. The clutch is thrown out of engagement at the completion of one revolution of the cam shaft.

Other objects and advantages of the invention will hereinafter appear and the novel features thereof will be specifically defined by the appended claims.

The invention, in its preferred form, is clearly illustrated in the accompanying drawings, which, with the numerals of reference marked thereon, form a part of this specification, and in which—

Figure 1 is a substantially central vertical section, with parts in elevation, showing my improved construction.

Figure 2 is an elevation of the turn table actuating mechanism, with parts in section and portions broken away.

Figure 3 is an enlarged top plan of the clutch-operating arms.

Figure 4 is a side elevation of the same.

Figure 5 is a horizontal section as on the line 5—5 of Figure 1, looking down.

Fig. 6 is an enlarged detail, partly in section, of the selector mechanism.

Fig. 7 is a similar view showing the parts as having selected a record.

Fig. 8 is a diagrammatic view showing the cam laid out.

Fig. 9 is a detail in plan.

Fig. 10 is a section on the line 10—10 of Fig. 9.

Fig. 11 is an enlarged vertical longitudinal section of the carriage.

Fig. 12 is a detail in top plan, more particularly hereinafter referred to.

Like numerals of reference indicate like parts throughout the several views.

Referring to the drawings

1 designates a frame, preferably of metal, containing the changing mechanism, the means for rotating the records for reproduction, and the record-selecting device. This is adapted to be affixed in the cabinet in any 60 suitable manner.

2 is a rotatable record-support, herein-after referred to as the turn table, carrying the records for reproduction, supported on a vertical spindle 3 by means of slot and key

65 4. 5 is a friction hub having a flat hori-

zontal upper surface in contact with a similar lower surface of the turn table 2, serving as means to rotate said turn table, pressure of contact being maintained by a spring 6 accommodating various elevations of the 70 turn table. The friction hub 5 has at its lower end long slots 5^a or teeth engaging and forming a part of a worm gearing of which 7 is a driving worm. The spindle 3 extends through the friction hub 5, being 75 loosely passed through the friction hub 5 and through a vertical column in the frame 1, into an end thrust bearing 8. This thrust bearing has on one side an extension 9, which extends through a vertical slot in 80 the column of the frame 1.

10 is a vertical cylindrical cam, the track of which engages the under surface of the extension 9 on the thrust bearing 8; rotary motion on its cylindrical axis causes the 85 cam 10 to thereby raise or lower the thrust bearing 8, the spindle 3, and the turn table 2 with the record or records thereon. Considering Fig. 8 which is a development of the cam 10, E represents the relative playing elevation of the turn-table. As the cam rotates in the direction of the arrow, the turn-table lowers corresponding to point A, and remains in this position from A to B while the tone arm is swept across and clear 95 of the record. The turn-table then rises to point C where a new record is taken on or the records on the turn-table restored, depending upon the action of the selectors. The turn-table is then lowered to D while the 100 tone arm is swung over to a point where the needle is just above the beginning of the sound groove in the record, at which position the turn-table is raised gently engaging the record with the needle in the playing position E. The cam 10 is caused to rotate by engagement of a toothed clutch 12, the driving member of which is a part of the worm gear 11 engaged in mesh with the worm 7. The driven member of said toothed 110 clutch is the hub of the disc cam 21 which is fastened to the vertical shaft 13 at the lower end of which is a feather key engaging a vertical slot in the hub of the cam 10.

The driven member of the toothed clutch 115 12 is held, against gravity out of engagement, by two pins engaged in an annular groove in the hub of the cam 21, said pins being a part of a substantially U-shaped frame 22, shown in detail in Figures 3 and 120 4. The other end of the frame 22 is a hub 61, firmly connecting the two extensions 22^a, 22^b, containing the pins 22^c, and mounted on the horizontal shaft 67 about which it is allowed to turn. At one side of the frame 22 125 is an arm 23 also mounted and free to turn on the shaft 67, said arm containing a pin 62 extending across and through recesses 22^d in the frame 22, as seen in Figure 3, serving as a stop against which said frame rests in 130

said recesses, being pressed against the pin 62 by the action of a spring 60, one end of which spring is held by the pin 62, the other end pressing upward on the pin 63 which is a part of the frame 22.

5 a part of the frame 22.
Now, the shaft 13, the cam 21 with its
toothed clutch hub, the frame 22 which sup-
ports these members, and the arm 23, which
is connected to the frame 22 by the spring
10 60 are all suspended against gravity by the
detent lever 65 fulcrumed at 66 and form-
ing a detent on the extension 68 of the arm
23. Thus if the lever 65 is partially rotated
15 on the fulcrum or pin 66 it is plainly evident
that the detent will be released and the up-
per member of the toothed clutch 12 will fall
into engagement with its lower member,
thereby rotating the cam 21 and the cam 10
20 on their common vertical axis. At the be-
ginning of this rotation in the direction indi-
cated, the pin 25 which is a part of the cam
21, Fig. 5, cams past the extension 24^a per-
mitting the free end of the arm 24 to swing
25 by pressure of the spring 26 over the pin
22^c, which is part of the frame 22, locking
said frame in position where the clutch is
engaged.

In the further course of rotation, near the end of the cycle of operation the hook 64 slides along the lower edge of the wedge shaped extension 68 and raises the arm 23, at which time the detent lever 65 is restored under the extension 68 in a manner described later on. Now in the raising of the arm 23, the stop pin 62 is raised out of the recess on the frame 22, the tension of the spring 60 being thereby increased, the tendency of the spring now being to raise the frame 22 and to throw the clutch 12 out of engagement. The cam then travels to the extent of nearly a full revolution from its beginning, when the pin 25 again comes in contact with the extension 24^a on the arm 24, and by further rotation the arm 24 is swept to the side of the extended pin 22^c on the frame 22, letting the clutch out of engagement by action of the spring 60, the cam having completed one full revolution. A pin 25^d, see Figure 5, serves to limit the movement of the arm 24 when it swings over the pin 22.

50 when it swings over the pin 22. The mechanism by which the lever 65 is withdrawn from the detent or shelf 68 to permit the clutch 12 to drop into engagement will now be described. It constitutes 55 what I term a "tripping device". See Figures 4, 11 and 12. Lever 65 is pivoted at 66 (Fig. 4) and comprises a horizontally ex- 60 tends portion which extends freely through an elongated slot 81^a in a carriage member 81; and through an opening in a carriage member 82, by which it is operated. 65 The carriage member 81 is slidably mounted on horizontal shaft 80 which is rotated by a worm wheel associated with gear 11. Upon the horizontally extending top of carriage

80 is a pin 85, by means of which the carriage receives motion from the tone arm in a manner to be hereinafter described.

The carriage member 82 comprises an upwardly extending arm 82^a which embraces the shaft 80, forming a pivot about which this member is rocked. A second arm of this carriage embraces the lever 65, passes through a slot in the carriage 81 and terminates in a hook 83 engaging the carriage 81, and normally holding carriage 82 in the elevated position shown in Fig. 11. Upon the release of this hook engagement carriage 82 rocks as aforesaid, operating lever 65, releasing the detent 68, allowing the arm 23, which through the frame 22, carries the cam 21 with its tooth clutch hub, to fall into engagement with the worm gear 11, imparting rotation to the cam shaft 13.

rotation to the calm shaft 17. Considering the tripping device shown in assembly, Fig. 2, and in detail Fig. 12, first is the normal position Fig. 2 in which the lever 65 pivoted at 66 with an upward extension is serving as a detent at 68 to the lever 23, and the frame 22 shown in Figs. 3 and 4. The lever 65 is supported at its end by engagement in a slot in the carriage part 82. This part is supported in position by the spring 88. The upper part 81 of the tripper carriage also has a slot for the lever 65 and both parts are guided uprightly as the carriage slides on the threaded shaft 80. The part 82 has an upward extension through a recess in the part 81 forming a hook at 83. When the needle has traversed about two-thirds of the sound groove in the record, the forked lever 86 swinging on a common pivot 89, Fig. 5, with the lever 87 which is connected through the lever 54 to the tone arm, said forked lever 86 picks up the pin 85 and carries the part 81 to the right, Fig. 2. Immediately the part 81 engages the part 82 at the hook 83 carrying said part 82 in unison with the part 81. The part 82 has an extension forming a half-nut 84 which soon engages the thread of the shaft 80. Fig. 11 shows this engagement after the carriage has traveled part way. If at this point or any point after the end of the half-nut with the thread, 115

gagement or the ball-end with the needle stops at the end of the sound groove in the record, the part 81 consequently stops while the part 82 is carried further by the shaft thread to a point where the hook disengages the part 81 and this hook ¹²⁰ end of the part 82 drops by action of gravity as does the arm 65, thus releasing the detent at 68 allowing the cam shaft clutch to fall in as previously described.

fall in as previously described. The connection between the arm 87, Fig. 125, and the tone-arm is made by engagement of a bifurcated extension 100 on the arm 87 into which is slidably fitted a pin 103 which is adjustably mounted on the arm 54 which is affixed to the tone arm. The arm 87 has 130

an extension at one side to engage the track of the cam 21. The first movement upon rotation of the cam 21 is to carry the arm 87 to the extreme outer radius of the cam 5 holding it there while the turn-table is raised and lowered, then allowing the arm 87 to swing toward the centre of the cam by pressure of a spring 95 through an arm 93 pivoted at 94, to a point representing the 10 position of the needle over the beginning of the record sound groove. The action of the spring 95 is stopped at this point by a set screw 96. As the arm 87 is swept back from the position representing the position of the 15 needle at the end of the sound groove, as previously stated in connection with the tripping device, the tripper carriage, the parts 81 and 82 are also carried back to normal position by the forked end of the arm 20 86 engaged to the pin 85.

The frame 1 also contains the selecting device which consists of three rectangular posts 45 extending up and equi distant around the edge of the turn table. Each 25 post contains mechanism for selecting and restoring the records. Fig. 1 shows a sectional view of one of these selectors. 30 is a retaining latch protruding from the frame 45 toward the center of the turn-table. On 30 these latches the records rest when placed in the machine. 38 is a restoring latch which is contained in the latch 30. Both latches are movable on a common pivot 40. The lever 31 is pivoted at 41 and has at its upper end a finger 35 pivoted at 43. The arm 31 is held in normal position against the pressure of the spring 34 by restoring the latch 38 through the pin 32. The latch 38 is, in turn, pressed forward with the latch 40 30 by a spring 33 which is stronger than the spring 34. Referring to Fig. 7, the position of a selector is shown at the point of depositing a record on the turn-table. The turn-table has risen, its edge sliding against the protruding edge of the latch 30, pressing it back against the spring 33 into the frame 45, said frame being stationary in the frame 1. This allows the arm 31, with the finger 35, to be pressed forward by action of the 50 spring 34, at the same time keeping the latch 38 in its relative position to the latch 30 as the finger 35 protrudes, it enters between the bottom record and the rest of the stack allowing the bottom record to be deposited on the turn-table and retaining the others. It is evident that the finger 35 has fully engaged itself between the records before the latch 30 is depressed to the point of releasing the bottom record. As the turn-table 55 descends, the latches 30 and 38 resume their normal position by action of the springs, the finger 35 receding while the remaining records are retained on the latch 30. 37 is a vertically-adjustable screw member on the 60 frame 45 and having its lower end adapted to engage the finger 35, as seen in Figures 1, 6 and 7, to regulate the position of the latter so that it will be properly moved to enter between the lowermost record and the one next above it. Fig. 6 shows a selector in the 70 position of restoring the records. When the last record has been played and the turn-table rises, there being no record on the latch, the finger 35 in coming forth drops slightly at its free end by action of the 75 spring 31^a. As shown in Fig. 1, the spring 31^a tends to hold the finger 35 in position to engage the crevice between the records until the finger has protruded part way, it then exerts a pressure to push the finger down 80 which has no effect if the finger has engaged a record, if not, it is carried downward, swinging on pivot 43 and with it a small finger 36 contained within finger 35 on the same pivot, Fig. 6. Finger 36 is thereby 85 allowed to engage the latch 30, which in traveling back into the frame, carries with it the fingers 36 and 35, the arm 31, and the pin 32. As the pin 32 comes to its normal position, the latch 38 may be extending forward by pressure of a light spring 39. As the records strike the protruding diagonal edge of the latch 38, said latch is easily depressed against the spring 39. The turn-table with records continues its upward travel until its upper surface is on a plane with the top horizontal edge of the latch 38, and the edge of the turn-table being beveled to conform to the latch 38, said latch is admitted under the records supporting them 100 while the turn-table descends. The latch 39 comes forward to its normal position by pressure of the spring 33 and the selector is again ready to select the bottom record. The turn table then descends empty. When 105 the turn table is raised by the cam 10 in the manner hereinbefore described, it comes to a certain point of elevation depending upon the number of records deposited upon it, the fingers 35 detaining its upward travel. This reacts upon the cam 10, through the spindle 3, and the thrust bearing 8, and the cam by its rotation is forced down against its thrust bearing 15 on the post 16 and the spring 17, the ratchet teeth at the lower end 110 of the post 16 working through the dog 18 and comes to the notch representing the number of records on the turn table as the cam goes over its highest point, then, as the cam continues its rotation, the turn table 115 and the records descend to a point slightly below the playing level of the top record, and raises the record against the needle of the reproducer 52 which is predisposed at the outer edge of the record. This playing 120 elevation of the turn table always is respective to the elevation at which the turn table took on its new record.

The entire operation of this machine as described in the foregoing takes place in 130

the following succession; the principal functions are to swing the tone arm aside, then to raise the turn table to receive the record, thereby selecting the same, then to descend 5 and take up the needle which has been swung back to the beginning of the sound groove in the record.

Starting at the point of beginning of a new record, the needle travels in or traverses 10 the sound groove to the end, the reproducer and the tone arm traveling slowly toward the centre. With this crosswise movement of the tone arm, the arm 54 affixed thereto carries the arms 87 and 86 with it, after 15 two-thirds of its travel throwing into action the carriage 81 as previously described.

At the end of the sound groove the tone arm remains stationary stopping the member 81 of the carriage, resulting in the engagement 20 of the clutch in the manner above described. Upon the first part of the rotation of the cam shaft the turn table is lowered by the cam 10 to clear the needle of the record, the tone arm being then swept 25 back by the cam 21. At this point the dog 18 is thrown out of engagement with the ratchet teeth on part 16, allowing the spring 17 to raise the cam 10 and consequently the turn-table and records. Figs. 10 and 11 30 show how the cam 112 which is carried in rotation by a pin 112^a, slidably fitted through the cam 10, engages the pin 19 thereby pressing the dog 18 out of engagement with the teeth in post 16, allowing the spring 17 to 35 raise the cam 10 and consequently the turn-table etc. The track of the cam 10, in rotation continues this raising motion of the turn-table to the point of taking on a record or restoring the records, as above described.

40 If a new record has been taken on, the turn table descends to a point where the upper surface of the record is below the point of the needle, whereupon the tone arm is carried back by the arm 93 under the action of 45 the spring 95, stopped by adjustment 96 at a point just above the beginning of the sound groove of the record. The record then rises gently against the needle. One complete revolution of the cam shaft has 50 completed the entire operation. It will be observed that as the turn table departs from the friction hub in rising, its rotation will cease, but as it returns to contact with said hub rotation is again imparted thereto.

55 The source of power employed may be that which may be found most expedient. For instance, an electric motor, not shown, may be used, in this case belted to the pulley 71 on the shaft 70, which drives the entire 60 mechanism 72 being a governor of any well known or approved type.

From the foregoing it will be seen that I have devised a simple, efficient and practical mechanism for the purpose set forth, 65 and while the structural embodiment of the

invention as herein disclosed is what I, at the present time, consider efficient, and perhaps preferable, it will be evident that various modifications in details of construction, arrangement of parts etc. may be resorted to without departing from the spirit of the invention or sacrificing any of its advantages. I therefore do not wish to restrict myself to the particular construction herein shown and described, but reserve the right to make such changes, variations and modifications as come properly within the scope of the protection prayed. —

What is claimed as new is:—

1. In a talking machine, means for holding a stack of records, and a turntable movable upwardly vertically toward said stack in axial alinement with the records sustained by said holding means to receive a record from said stack. —

2. In a talking machine, means for holding a stack of records, and a turntable movable vertically in axial alinement with the records sustained by said holding means to receive a record from the stack. —

3. In a talking machine, means for holding a stack of records, and a turntable movable vertically in axial alinement with the records sustained by said holding means to receive a record from the stack and to restore records to their normal position. —

4. In a talking machine, means for holding a stack of records, a turntable movable vertically toward said stack in axial alinement with the records sustained by said holding means, and means for releasing a record from the stack for delivery to the turntable when the latter is in its elevated position. —

5. A turntable, means for holding records in alinement with said turntable and means for restoring records to said holding means by vertical movement of the turntable in axial alinement with the records. —

6. In a talking machine, a turntable, means for holding a stack of records in axial alinement with said turntable, and means for releasing a record from the stack, said turntable being movable vertically in axial alinement with the stack of records to receive, while in its uppermost position, such released record. —

7. In a talking machine, a turntable, means for holding a stack of records in axial alinement with said turntable, means for releasing a record from the stack, said turntable being movable vertically in axial alinement with the stack of records to receive, while in its uppermost position, such released record, and means for removing a record from the turntable when moved to its uppermost position, to restore it to the stack. —

8. In a talking machine, means for holding a stack of records, a turn-table movable

- vertically in axial alinement with the records to receive a record, and means for releasing a record from a pile of the same, to be taken to playing position by the turn-table.
9. In a talking machine, means for holding a stack of records, a turn-table movable vertically in axial alinement with the records to receive a record from a stack, and means for disengaging a record from the stack to permit the turn-table to take and then be lowered, with such record, to playing position.
10. In a talking machine, means for holding a stack of records, a turn-table, means permitting of moving the same vertically in axial alinement with the records to receive a record from a stack, and means permitting of lowering the turn-table with such record to playing position.
11. In a talking machine, means for holding a stack of records, a turn-table, means for raising the same vertically in axial alinement with the records to position to receive the bottom record of a stack, means for delivering such bottom record to the turn-table, and means permitting of lowering the turn-table and record to playing position.
12. In a talking machine, means for holding a stack of records, a turn-table, movable vertically in axial alinement with the records to receive a record, and means actuated by the raising of the turn-table to release a record.
13. In a talking machine, means for holding a stack of records, a turn-table, means for moving the same upward to receive a record, means permitting of lowering the turn-table with its record, and means for then raising the turn-table to bring the record up against the needle.
14. In a talking machine, means for holding a stack of records, a turn-table, means for moving said turn-table upwardly in axial alinement with the records in proximity thereto to receive a record, and means for swinging the tone arm to one side.
15. In a talking machine, means for holding a stack of records, a turn-table vertically movable to receive a record released from a stack, means for swinging the tone arm to one side prior to the raising of the turn-table, and means for releasing a record from the stack.
16. In a talking machine, means for holding a stack of records, a turn-table vertically movable to receive a record released from a stack, means for swinging the tone arm out of the path of the turn-table prior to its upward movement, and means actuated by the movement of the turn-table for releasing the record from the stack.
17. In a talking machine, means for holding a stack of records, a turn-table vertically movable in axial alinement with the records to receive a record, means permitting of lowering the turn-table and its record to a point below the playing level of the upper record on the turn-table, and means for raising the record up against the needle and into playing position.
18. In a talking machine, means for holding a stack of records, a turn-table, means for swinging the tone arm to one side, means for raising the turn-table in axial alinement with the records to position to take on a record, and means for thereby releasing the record.
19. In a talking machine, means for holding a stack of records, a turn-table, means for raising the same in axial alinement with the records to receive a record released from a stack, and means for determining the playing elevation of the turn-table in accordance with the elevation of the turn-table and the number of records thereon.
20. In a talking machine, means for holding a stack of records, a turn-table, means for raising the same in axial alinement with the records to receive a released record from a stack, and means actuated by the contact of the table in its upward movement for releasing a record from the stack.
21. In a talking machine, means for holding a stack of records, a turn-table movable vertically in axial alinement with the records to receive a released record from said stack, and means for moving said turn-table in axial alinement with the records from the plane of the top record thereon to the under surface of the bottom record in the stack.
22. In a talking machine, means for holding a stack of records, a turn-table movable vertically in axial alinement with the stack of records to receive a record from said stack, means for primarily swinging the tone arm to one side, means permitting of lowering the turn-table and its record to a point below the needle and then raising the turn-table to bring the record into playing position against the needle.
23. In a talking machine, means for holding a stack of records, a turn-table, means for moving the same upward in axial alinement with the stack of records to receive a record released from said stack, record-releasing means actuated by the upward movement of the table, tone-arm swinging means, and means for restoring the records from the turn-table to the stack.
24. In a talking machine, means for holding a stack of records, a turn-table, and means for moving the same vertically in alinement with the stack of records to restore records to said holding means.
25. In a talking machine, means for holding a stack of records, a turn-table, means

- for moving the same upward in axial alinement with the stack of records to return records to the stack, and means for delivering such records from the turn-table.
26. In a talking machine, means for supporting a stack of records, a turn-table, means for moving the same upward in axial alinement with the stack of records to receive the record, means for lowering the same, and the record, and means permitting of moving the turn-table and record upward and returning the record to its normal position.
27. In a talking machine, means for holding a stack of records, a turn-table, and cam means for raising the same in axial alinement with the stack of records.
28. In a talking machine, means for holding a stack of records, a turn-table, and means for raising the turn-table to receive a record from the stack, permitting the lowering of the turn-table by its own weight, and raising the turn-table to cause the record to engage the stylus.
29. In a talking machine, means for holding a stack of records, a turn-table, and cam means for raising the same in axial alinement with the stack of records and for swinging the tone arm to one side.
30. In a talking machine, means for holding a stack of records, a turn-table, and cam means for raising the same in axial alinement with the stack of records and for permitting the lowering of the turn-table for swinging the tone arm to one side.
31. In a talking machine, means for holding a stack of records, a turn-table, cam means for raising the same in axial alinement with the stack of records and cam means cooperating therewith to swing the tone arm out of the path of the turn-table.
32. In a talking machine, means for holding a stack of records, a turn-table, and cam means for raising and permitting the lowering of the same in axial alinement with the stack of records to receive a record and then to bring the same to a position below the needle.
33. In a talking machine, means for holding a stack of records, a turn-table, cam means for raising the same to receive a record from the stack, and then permitting of lowering the same to playing position, the turntable being movable in axial alinement with the stack of records in both its up and down movements, and cam means operating in conjunction with the first-named cam means to swing the tone arm out of the path of the turn table in its movements.
34. In a talking machine, a turn-table, and means embodying a cam shaft with a cylindrical cam with curved track for raising and permitting lowering of the turn-table.
35. In a talking machine a turn-table, and a cam shaft with a cylindrical cam with curved track for raising and permitting the lowering of the turn-table, and a disc cam for swinging the tone arm to one side.
36. In a talking machine, a turn-table, a cam shaft with cams for raising and permitting of lowering the turn-table and swinging the tone arm to one side, and a worm gear for rotating the turn-table.
37. In a talking machine, a turn-table, a cam shaft with cams for raising and permitting of lowering the turn-table and swinging the tone arm to one side, and a worm gear for rotating the turn-table, the said worm gear cooperating with the said cam shaft.
38. In a talking machine, a turn-table, a cam shaft for raising and permitting of lowering of the turn-table, and a two-part carriage a revoluble threaded shaft. cooperating with the said cam shaft for releasing the said threaded shaft.
39. In a talking machine, a turn-table, a cam shaft and cylindrical cam for raising and permitting of lowering the same, and a two-part carriage cooperating with said cam shaft the said two parts of the carriage being adapted to move in unison in their motion.
40. In a talking machine, a turn-table, a cam shaft with means for raising and permitting of lowering the turn-table and swinging the tone arm to one side, and a two-part carriage cooperating with the cam shaft, one part of the said carriage having movement after the other part stops.
41. In a talking-machine, a turn-table, a cam shaft and cams for raising and permitting of lowering the same and for moving the tone arm to one side, and turn-table rotating means operable to rotate the cam shaft.
42. In a talking machine, a tripping device embodying two-part carriage, one part of which has movement for a portion of its travel after the other part stops.
43. In a talking machine, a tripping device embodying two-part carriage, one part of which has movement after the other part has stopped moving, and means whereby the motion of the two parts in synchronized.
44. In a talking machine, means for holding a stack of records, a turntable movable vertically in axial alinement with the stack of records, elevating means therefor, and means for adjusting the same to the varying elevations of the turn-table.
45. In a talking machine, means for holding a stack of records, a turntable movable vertically in axial alinement with the stack of records, a ratchet and means cooperating with the ratchet for adjusting the varying elevations of the turn-table according to the height to which the turn-table is to be moved upon taking on a record.

46. In a talking machine, means for holding a stack of records, a turntable movable vertically in axial alinement with the stack of records, record-releasing means operable by vertical movement of the turn-table. 5
47. In a talking machine, means for holding a stack of records, a turntable movable vertically in axial alinement with the stack of records, record-releasing means having portions disposed in the path of the vertically-movable turn-table. 10
48. In a talking machine, means for holding a stack of records, a turntable movable vertically in axial alinement with the stack of records, record-releasing means having a portion operable by the vertical movement of the turn-table, and a pivoted finger movable between the records in a stack. 15
49. In a talking machine, record-releasing means embodying fixed uprights and pivoted means within the same operable by the vertical movement of the turn table to release and deliver a record to the turn-table. 20
50. In a talking machine, means for holding a stack of records, a vertically-movable turn-table movable in axial alinement with the stack of records, and a step by step means cooperable therewith to lower the table. 25
51. In a talking machine, a turn-table mounted for movement toward a stack of records supported in axial alinement with said turn-table to receive a record from such stack. 30
52. In a talking machine, a turn-table mounted for movement toward a stack of records supported in axial alinement with said turn-table to receive a record from such stack, said turn-table being returnable by its own weight. 40
53. In a talking machine, a turn-table mounted for movement toward a stack of records supported in axial alinement with said turn-table to receive a record from such stack, and means actuated by the movement of the turn-table to deliver and to return to the stack a predetermined record. 45
54. In a talking machine, a turn-table movable vertically toward a record to receive the same and returnable by gravity with said record. 50
55. In a talking machine, a record magazine, a turn-table, means for moving the turntable toward the magazine to receive a record from the same, and means to return the record to the magazine by a like movement of the turntable, substantially as set forth. 55
56. In a talking machine, a record magazine, a turntable, means for moving the turntable toward the magazine to receive a record from the same, and means to return all the records on the turntable simultaneously to the magazine by a like movement of the turntable, substantially as set forth. 65
57. In a talking machine, a record magazine, a turntable, means for feeding the records successively to the turntable, and means for returning all the records together to position in the magazine by movement of the turntable, substantially as set forth. 70
58. In a talking machine, a record magazine, a turntable beneath the same, means for feeding the records successively to the turntable, and means for returning all the records to the magazine by an axial movement of the turntable, substantially as set forth. 75
59. In a talking machine, a record magazine, a turntable, and means for moving the turntable from playing position into position to permit isolation of and to receive one of said records and thereafter returning the turntable to playing position, substantially as set forth. 80
60. In a talking machine, a record magazine, a turntable, means for moving the turntable into position to permit isolation of and to receive one of said records, and means for moving the turntable to return all the records simultaneously to the magazine after the last record has been reproduced, substantially as set forth. 85
61. In a talking machine, a record magazine, a turntable beneath the same, means for elevating the turntable after each record is played to receive an additional record from the magazine and automatic means for varying the position of the turntable relative to the elevating means, substantially as and for the purpose set forth. 90
62. In a talking machine, a magazine for holding a stack of records, a turntable, means for bringing the turntable and the stack into juxtaposition after the playing of each record, means to add a new record to the turntable at such time, and means for transferring all the records on the turntable back to the magazine at one time, substantially as set forth. 100
63. In a talking machine, a turntable, means for supporting a stack of records embodying fixed uprights and pivoted record releasing means within the same operable by the vertical movement of the turntable to release and deliver a record to the turn-table, substantially as set forth. 110
64. In a talking machine, a turntable, means for supporting a stack of records above the same, means for elevating the turn-table to receive a record, and means actuated by the movement of the table to separate the lowermost record from the stack, substantially as set forth. 120

In testimony whereof I affix my signature.
JAMES E. STOUT.
